PHOTOFASH LAMP

Ralph E. Andrea, Dayton, Ohio

Application January 2, 1947, Serial No. 719,647

7 Claims. (Cl. 67—31)

(Granted under the act of March 3, 1883, as amended April 30, 1928; 370 O. G. 757)

1

The invention described herein may be manufactured and used by or for the Government for governmental purposes without payment to me of any royalty thereon.

This invention relates to a photoflash lamp that is proof against other than intended ignition by electric charges or currents.

One object of the invention is to provide a photoflash lamp that is proof against ignition from induced electrical currents which enter the lamp from sources other than through the base of the lamp.

Another object is to provide a photoflash lamp that is proof against ignition by stray high-frequency and other electric currents or waves. Such phenomena are often present during military usage of photoflash lamps when subjected to electrical transmission from radar and radio stations.

Another object is to provide a sleeve of dry paper or other sheet material to be shipped over the lead-in wires of a foil- or wire-filled photoflash lamp during manufacture, thus insulating the filament and primer from any electrical charge which may be present on the foil or wire.

In the drawing:

Fig. 1 is an elevation of my photoflash lamp showing the sleeve in place;

Fig. 2 is an elevation of the sleeve alone; and

Fig. 3 is a cross section of my lamp taken on the line 3—3 of Fig. 1.

In Fig. 1, 10 is a screw- or other style base, 11 is the usual glass envelope or globe. 15 is a filament between the primers 19 and 19a used commercially in photoflash lamps. 16 is a paper or other material sleeve which I have invented and is mounted over the glass stem 13 and around the lead-in wires 14 and 14a during the manufacture of the lamp. It has an originally cylindrical form, as shown in Fig. 2, but the shape becomes distorted upon mounting. The reason is that the top of glass stem 13 has an oval cross-section, which the sleeve 16 assumes.

The sleeve 16 as shown in the figures has a number of gored areas 17 in its upper end, thereby giving that end a deeply crenelated appearance. The areas 17 perform the function of allowing heat from the filament 15 and flame from the filament and primer to reach the foil or wire filling 12 to ignite it. The bulb 11 contains oxygen to support combustion of the foil or wire 12.

The sleeve 16 may be made of seamless tubing, preferably of paper or permissibly of fiber or plastics. It must be substantially 100 per cent dry.

2

The preferred form is, however, seamed at 18 (Fig. 3) with a lap seam held with adhesive (not shown) of the pressure-sensitive type. Adhesive is also applied to the base of the sleeve at 20 on the inner edge thereof to assist in maintaining an erect position of the sleeve on the stem 13. The length and stiffness of the sleeve should be such that when it sits firmly on the stem 13, the upper edges will keep the foil or wire 12 from contact with filament. That part of the upper edges which comes above the primers 19 and 19a is preferably bent over them so as to meet or nearly meet in the center. The separation of the gores in length or diameter should not be so great that a prompt ignition cannot be achieved nor should they be longer than one-half the length of the sleeve.

The lamp is operated in the same manner as conventional photoflash lamps. No difficulty is experienced in igniting the foil or wire filling when the current from standard wiring circuits is used or even when the current source is from a battery of adequate amperage and voltage and enters the lamp through its proper electrical terminals. The current that the battery will give should not be less than that required by the rating of corresponding conventional lamps.

The invention claimed is:

1. In a photoflash lamp, a transparent gas-tight envelope, a base, a glass stem arising from said base within said envelope, lead-in wires extending through said stem, a filament extending between said lead wires and in contact therewith, ignition means in contact with said filament, a filling of brightly combustible metal, a filling of oxygen in said envelope, a dry sleeve of flexible cellulosic sheet material mounted on the filament-supporting glass stem and supporting said combustible metal filling and preventing contact between said filament and said combustible metal filling, said sleeve being deeply crenelated in a multiplicity of places around its top edge.

2. A photoflash lamp according to claim 1 in which the crenelated portions of the sleeve are of greater width at the top of the sleeve than at their lower ends.

3. A photoflash lamp according to claim 1 in which the crenelated top edges of the sleeve are turned toward the axis of the sleeve.

4. A photoflash lamp according to claim 1 and in addition a coating of pressure-sensitive adhesive on the lower inner edge of the sleeve.

5. A photoflash lamp according to claim 1 in which the sleeve is made of paper.

6. A photoflash lamp according to claim 1 in which the sheet material of which the sleeve is made is lap-joined to itself to make a tube.

7. A sleeve of dry cellulosic sheet material of moderate stiffness having dimensions enabling it to be fitted over and be mounted upon the glass filament supporting stem of a photoflash lamp, said sleeve being deeply multi-crenulated at one end, and coating of pressure-adhesive material on the inner surface of the non-crenulated end of said sleeve.
